Primary Examiner — Mimosa De(74) *Attorney, Agent, or Firm* — Greenberg Traurig, LLP(57) **CLAIM**

The ornamental design for a chair, as shown and described.

DESCRIPTION

FIG. 1 is a front right perspective view of a chair of our new design;

FIG. 2 is a front view of the chair shown in FIG. 1;

FIG. 3 is a rear view of the chair shown in FIG. 1;

FIG. 4 is a left side view of the chair shown in FIG. 1;

FIG. 5 is a right side view of the chair shown in FIG. 1;

FIG. 6 is a top view of the chair shown in FIG. 1;

FIG. 7 is a bottom plan view of the chair shown in FIG. 1; and,

FIG. 8 is a rear bottom perspective plan view of the chair shown in FIG. 1.

The broken lines are included to show features that form no part of the claimed design.

1 Claim, 8 Drawing Sheets(56)
